UNITED STATES PATENT OFFICE

96,398

DESIGN FOR A DRESS

Cassandra K. La Ruea, New York, N. Y.

Application July 6, 1935, Serial No. 57,542

Term of patent 3½ years

To all whom it may concern:

Be it known that I, Cassandra K. La Ruea, a citizen of the United States of America, residing in Manhattan, county of New York, and State of New York, have invented a new, original, and ornamental Design for a Dress, of which the following is a specification, reference being had to the accompanying drawing, forming part thereof, wherein,

Figure 1 is a front view of a dress showing my new design.

Figure 2 is a rear view of the dress shown in Figure 1.

The circular elements extending diagonally

across the back of the waist member of the dress, represent buttons, which extend over the opening of the dress.

The cross hatched lines on the front and back of the waist and sleeve members of the dress represent a transparent netted fabric.

The floral elements extending along the front and back of the waist represent applique embroidery.

I claim:

The ornamental design for a dress substantially as shown and described.

CASSANDRA K. LA RUEA.
